CLOSURE CAP FOR CONTAINERS

Walter R. Frank, Elmhurst, Ill., assignor to Aerosol Research Company, a corporation of Illinois

Application June 20, 1955, Serial No. 36,578

Term of patent 14 years

(Cl. D58—26)

Fig. 1

Fig. 2

Fig. 2 is a top plan view thereof;

Fig. 3 is a side elevational view thereof; and

Fig. 4 is a bottom plan view thereof.

I claim:

The ornamental design for a closure cap for containers, substantially as shown.
